UNITED STATES PATENT OFFICE.

BLYTHE J. MINNIER, OF WATERTOWN, NEW YORK, AND HENRY F. BICKEL, OF PLAINFIELD, NEW JERSEY.

AUTOMATIC TRAIN-PIPE CONNECTOR.

1,424,582.

Specification of Letters Patent.

Patented Aug. 1, 1922.

Application filed February 26, 1920. Serial No. 361,494.

To all whom it may concern:

Be it known that we, BLYTHE J. MINNIER and HENRY F. BICKEL, citizens of the United States, residing, respectively, at Watertown, in the county of Jefferson and State of New York, and at Plainfield, in the county of Union and State of New Jersey, have invented certain new and useful Improvements in Automatic Train-Pipe Connectors, 10 of which the following is a specification.

This invention relates to train pipe connectors for railway cars, and particularly to the automatic type of connector in which a connector head mounted on one car is automatically brought into connecting relation with a similar head on an adjacent car by the coupling of the cars together.

The principal features of novelty are, first, the mode of supporting the connector head, so that it maintains a definite position and alinement when the cars are uncoupled, but is free to have universal movement of considerable range when the cars are coupled, and so that any connector head and its 20 component parts can be dismounted and replaced when the cars are coupled as well as when they are uncoupled; second, a removable gasket carrier capable of removal while the cars are coupled to permit the renewal of worn or defective gaskets; and, third, the combination in a single structure of the features above mentioned, the special supporting means being peculiarly adapted to use with the removable gasket carrier because 30 of the facility with which the connector heads may be slightly separated, while the cars remain coupled, to free the gaskets and permit the withdrawal of the gasket carrier.

The maintenance of uniform position and alinement in the uncoupled condition of the cars assures accurate engagement and registration of the connector heads during the coupling operation. This reduces wear and tear and ensures certain operation.

45 After the cars have been coupled, the interengagement of the connector heads will maintain their alinement with each other, and it is accordingly important that each head should have considerable universal 50 movement with reference to its respective car, since the relative movement of the cars is considerable. The present invention

leaves both connector heads free when the cars are coupled, except that each is subjected to spring pressure urging it into sealing engagement with the other.

Another desirable result secured by the invention is that the main springs are capable of adjustment whether the cars be coupled or uncoupled. Adjustment of the 60 spring does not affect the position assumed by the connector head when the car is uncoupled; consequently the adjustment of the spring has no disturbing effect on the automatic engagement of the connector heads 65 during the coupling operation.

Not only may such adjustments be made, but it is possible to dismount a connector head while the cars remain coupled, and it is possible to replace any component part by 70 a relatively simple operation.

From the standpoint of practical maintenance and operation, the ability to adjust and replace parts while the cars remain coupled is a feature of the utmost importance. 75 There are many occasions when it is imperative that such replacements or adjustment be made without uncoupling the cars, and the present invention therefore greatly extends the practical utility of automatic train 80 pipe connectors.

The invention is peculiarly applicable to that type of automatic connector which is mounted on the automatic couplers forming a part of the draft gear of standard railway 85 cars. Such an embodiment of the invention is shown in the accompanying drawings, in which,—

Fig. 1 is a side elevation of two connector heads, the connector heads being shown 90 wedged back to free the gaskets, and one gasket carrier being shown withdrawn. In this view the automatic coupler heads, from which the connector heads are suspended, are shown in outline only, and the flexible 95 pipe connections to the connector heads are omitted;

Fig. 2 is a side view, principally in section, of a single connector head and its support. The flexible pipe connections to the 100 connector head are omitted, and the automatic coupler head upon which the connector head is supported is shown in outline only;

Fig. 3 is a section on the line 3—3 of Fig. 2;

Fig. 4 is a horizontal axial section through a connector head and the carrier head upon which it is supported;

Fig. 5 is a front elevation of a connector head and its support; and

Figs. 6, 7 and 8 are, respectively, vertical section, front elevation and plan, of the gas-
ket carrier.

Referring to Fig. 1, 11 and 12 are automatic coupler heads forming a part of the draft rigging. These are illustrated merely to show the mode of supporting the connector heads hereafter described. Since the connector head carried by each of the couplings 11 and 12 is a duplicate of that carried by the other, a description of one will suffice. Referring now particularly to Figs. 2 to 5 inclusive, 13 is a depending bracket, which may either be formed integrally with, or be bolted to, a coupler head 11. The form and dimensions of the bracket 13 depend somewhat on the form of the coupler head 11, the dimensions being such as properly to position the connector head supported by the bracket with reference to the coupler 11.

Bracket 13 terminates at its lower end in a rectangular boss 14. This is embraced between jaws 15 and 16 on the upper end of a carrier 17 which terminates at its lower end in an approximately spherical carrier head 18. A pair of bolts 19 pass through the jaws 15 and 16 and the boss 14 and thus connect the member 17 to the bracket 13. In order to secure a tight fit, the jaws 15 and 16 terminate in overhanging flanges 20 which engage behind the boss 14, and wedge 21 is driven under the boss 14 to take up the slack. The projecting end of this wedge is bent to prevent it working out, as is shown in Fig. 2.

As is best shown in Figs. 2 and 3, the carrier 17 is tubular and is reinforced by a web 22 which is extended at the rear to form an alinement stop 23. A companion alinement stop 24, is formed on the rear of the spherical carrier head 18 near its lower extremity. The carrier head 18 is formed at each side with a trunnion 25, and has on its front and rear faces openings 26, which are reinforced by inwardly projecting flanges 27. The opening at the bottom of the head 18 is merely for convenience in manufacture.

Mounted on the carrier head 18 is the connector head indicated generally by the numeral 28. This is formed integrally with a supporting yoke consisting of two side bars 29, parallel to each other, and a connecting ring 30 bridging the rear ends of the bars 29. The front face of the ring 30 is formed with a bearing seat fitting the rear spherical face of carrier head 18. Each of the side

bars 29 has a slot 31 to receive the trunnions 25, formed on the sides of the carrier head 18. The slots 31 are narrowed at their extreme rear portions to form seats 32, (best shown in Fig. 1) which closely fit the trunnions 25. The connecting ring 30 has at its top and bottom stops 33 and 34 so dimensioned that when the carrier head 28 is at the limit of its forward motion these stops abut against the alinement stops 23 and 24. Thus when ring 30 is against head 18, stops 33 and 34 engage alinement stops 23 and 24 and trunnions 25 are confined in seats 32. This is the means used to secure positive alinement when cars are uncoupled.

A tension rod 35 passes through the openings 26 and is threaded at its forward end. A bearing cup 36 which fits the forward spherical face of the carrier head 18 is screwed into the forward end of the rod 35 and is pinned in place as indicated at 37. The rear end of the rod 35 has a threaded portion 38 of considerable length, and a relatively long sleeve nut 39 is threaded thereon. This is locked by a check nut 40. Swiveled on nut 39 is a spring seat 41. Confined between the spring seat 41 and a spring seat 42, formed on the rear face of the yoke ring 30, is a conical spiral spring 43. This is the main spring which holds the connector head 28 at the forward limit of its motion whenever the cars are uncoupled, and, with the similar main spring of the companion connector head, produces the sealing pressure between the connector heads of coupled cars.

To permit a connector head to be forced rearward in opposition to its spring 43, for certain replacement operations, the side bars 29 are formed with bosses 44, and sufficient space is left between the sides of the carrier head 18 and the side bars 19 to receive a wedge 45, shown in Fig. 1. The wedge is not a part of the connector structure, but is merely a convenient tool to enable a mechanic upon occasion to force the connector head back with reference to the supporting head 18.

The connector head 28 has a contact face 46 designed to abut against the similar face of a companion connector head. The connector head is further provided with staggered guiding jaws 47 and 48 of usual form which guide the face 46 of one connector head into proper registering contact with the face of a companion connector head. The connector head, at the rear of the face 46, is cored out to form chambers, one for each pipe line carried by the car. In the example illustrated these are chambers 49, having a threaded connection 50 for the signal air pipe, chamber 51 having a threaded connection 52 for the air brake pipe or "train pipe", and chamber 53 having a threaded connection 54 for the steam pipe.

Each of these chambers has a port or opening leading through the contact face 46, the opening from chamber 49 being indicated at 55, the opening from chamber 51 being indicated at 56, and the opening from chamber 53 being indicated at 57. The openings 55, 56 and 57 are arranged in vertical alinement, as has been customary in past practice. Each is equipped with a projecting rubber gasket which seals against a corresponding gasket carried by a coacting connector head. Heretofore these gaskets have been inserted from the front and hence could not be removed without uncoupling the cars. To obviate this defect it has been proposed to insert the gaskets from the rear through ports formed through the rear of the connector head, but this construction has proved unsatisfactory in service, partly because of the inaccessibility of the ports and partly from inherent difficulties in securing tight sealing with gaskets so mounted.

In the present structure the gaskets are mounted in a carrier plate which slides into place from the top of the connector head, and is held in a confining guideway formed in the contact face 46. This carrier plate 58, as best shown in Figs. 2 and 4, slides in and is confined by the overhanging edges of a dovetail guideway formed in face 46. At its upper end carrier plate 58 has a lug 59 by which it may be withdrawn. Normally the plate 58 is held in place by a nut 60 threaded on stud 61, the stud passing through a hole in lug 59, and the nut being held by a spring lock-washer 62 or the equivalent.

The carrier plate shown in the drawings carries only the gaskets for the two air lines,—i. e., the signal and brake pipes. It therefore has (see Figs. 6, 7 and 8) two openings 63 and 64 which register, when the carrier plate is in place, with openings 55 and 56 in the contact face of the connector head. The openings 63 are counter-bored on the rear face of the carrier plate 58 as shown at 65 and 66, the counterbores forming seats for the flanges of the flanged gaskets 67 and 68 which are inserted from the rear of the carrier plate when the latter is withdrawn from the connector head. When the carrier plate is in place the gaskets are closely confined against the connector head, and their central portions extend through, and beyond, the front face of the carrier plate so that tight joints are assured between each gasket and its connector head and between opposed gaskets on two connector heads when in connecting relation.

The usual type of steam line gasket is shown on the steam line at 69 and the usual automatic valve is indicated at 70.

In order that the invention may be fully understood the methods used in making ad-

justments and replacements will be described.

To renew gaskets between the heads of two coupled cars one connector head (for example the right hand head in Fig. 1) is locked back by inserting a wedge 45 behind trunnion 25. Since this wedge is not to force the head back, but is merely to prevent the head from moving forward, the wedge may merely be dropped into place from the top. A second wedge is then driven behind the trunnion of the other connector head drawing this head back and freeing the gaskets from pressure. The nut 60 and washer 62 are then removed and carrier 58 is withdrawn. Carrier 58 is not tightly fitted in its guide but should it stick it may be started by inserting a wedge under the lug 59. After renewing gaskets the carrier 58, washer 62 and nut 60 are re-placed and the wedges 45 are removed.

To adjust main spring 43, nut 39 is turned, after releasing nut 40. Spring 43 can be removed and replaced by removing nuts 39 and 40. Adjustment or removal and replacement of the spring can be made while the cars are coupled, as sleeve nut 39 is long enough to release tension on spring 43 before the nut reaches the end of rod 35. The opposed connector head should, however, be locked with a wedge.

To remove connector head 28 while cars are coupled the opposed connector head is first wedged as far back as possible. The flexible pipe connections (not shown) are broken. Then nuts 39 and 40 and spring 43 are removed as above described. Pin 37 is removed and bearing cup 36 is unscrewed from the end of rod 35, which is then withdrawn. The head 28 is slid back and lowered far enough to clear the opposed head, after which head 28 is swung to the side to clear trunnions 25. The parts are assembled in the reverse order.

The operation of the connector is as follows: When the parts are assembled and the cars are uncoupled, head 28 is held at the limit of its forward motion by main spring 43. Trunnions 25 are then in seats 32 and stops 33 and 34 abut against alignment stops 23 and 24. This holds head 28 in a definite position and in accurate alinement so that precise action will be secured during the coupling operation.

When the cars are coupled the heads 28 are each forced back so that trunnions 25 are in the wide portions of slot 31 and stops 23, 24, 33 and 34 are clear. Within reasonable limits, the heads 28 have free universal movement. They are largely supported by the springs 43. The springs 43 are free to align themselves because each rod 35 has a universal ball and socket connection with the corresponding head 18. As a result the relative movements of the coupled cars are

4
absorbed in the springs and at the ball cups 36, so that wear and leakage between connector heads are minimized.

The structure therefore meets the requirements of hard service, first by accommodation to the severe movements of the coupled cars in a way to minimize wear, without sacrifice of precise automatic action in coupling, and second, by permitting replacement of parts while cars remain coupled. 10 The replacements and adjustments most frequently required are made with extreme ease and quickness.

The carrier plate, and the gaskets carried thereby, are in effect a removable sealing element, and in certain claims we use this term to designate these parts or their substantial equivalent.

Having thus described our invention what 20 we claim is:—

1. In an automatic train pipe connector, the combination of a carrier head having trunnions, a spherical front bearing face, and alinement stops; a slotted yoke loosely mounted on said trunnions and capable of 25 longitudinal and limited universal motion with reference to said carrier head when forced back to clear said alinement stops; a connector head mounted on the forward 30 end of said yoke; a tension rod having a socket bearing on the front face of said carrier head and extending to the rear of said carrier head; and a spring held by said tension rod and acting against the rear end 35 of said yoke to force said yoke and connector head forward.

2. In an automatic train pipe connector, the combination of a carrier head having trunnions and alinement stops; a yoke 40 bracing said carrier head and having slots to receive said trunnions, said slots being wider than said trunnions and formed with seats at their rear ends to confine said trunnions closely; a connector head mounted on 45 the front end of said yoke; a tension rod having a ball and socket connection with said carrier head and extending rearward from said carrier head; and a coiled spring surrounding said tension rod, supported at 50 its rear end thereby, and bearing at its front end against said yoke, said spring serving in the uncoupled condition of the device to hold said yoke at the limit of its forward motion against said alinement 55 stops, with said trunnions confined in said seats.

3. In an automatic train pipe connector, the combination of a carrier head having trunnions and alinement stops; a yoke 60 bracing said carrier head and having slots to receive said trunnions, said slots being wider than said trunnions and formed with seats at their rear ends to confine said trunnions closely; a connector head mounted on 65 the front end of said yoke; a tension rod

having a ball and socket connection with said carrier head and extending rearward from said carrier head; a coiled spring surrounding said tension rod, supported at its rear end thereby, and bearing at its front 70 end against said yoke, said spring serving in the uncoupled condition of the device to hold said yoke at the limit of its forward motion against said alinement stops with said trunnions confined in said seats; and 75 means for adjusting the tension on said spring.

4. In an automatic train-pipe connector, the combination of a connector-head having an orificed face adapted to be presented to 80 a companion connector head; and a sealing element having orifices surrounded by yielding sealing means, said orifices normally registering with the orifices in said face and said sealing element being capable 85 of removal as a unit by a sliding movement across said orificed face.

5. In a train-pipe connector, the combination of a pair of opposed orificed connector heads; resilient means urging said heads 90 toward each other; a pair of sealing elements, one for each head, each such element having an orifice surrounded by sealing means, such orifice normally registering with an orifice in the corresponding head, 95 and each sealing element being capable of withdrawal from between said heads in a direction transverse to the line of thrust between said heads, while said heads are in close proximity; and releasable means for 100 connecting each sealing element in registering position on its corresponding head.

6. In an automatic train pipe connector, the combination of an orificed connector head; a plate-like gasket carrier capable of 105 being slid into position edgewise across the orificed face of said connector head and adapted, when in position, to confine a gasket around said orifice; a gasket mounted in said carrier; and releasable retaining 110 means for said carrier, accessible in the coupled condition of the connector head, and serving to hold the carrier in place on said connector head.

7. In an automatic train pipe connector, 115 the combination of an orificed connector head; a plate-like gasket carrier capable of being slid into position edgewise across the orificed face of said connector head and adapted, when in position, to confine a gasket around said orifice; a gasket mounted in said carrier and capable of free withdrawal from the rear face of said carrier when the latter is removed from the connector head; and releasable retaining means 120 for said carrier, accessible in the coupled condition of the connector head, and serving to hold the carrier in place on said connector head.

8. In an automatic train pipe connector, 125

- the combination of a connector head having an orificed face adapted to be presented to a companion connector head; a gasket carrier with a flange-receiving recess; a flanged 5 gasket mounted in said carrier, and projecting through the same with its flange confined in said recess; and releasable retaining means for said carrier serving to hold it in position on said face with the gasket sealing 10 around said orifice, and to permit withdrawal of said carrier and gasket across the face of said connector head.
9. In an automatic train pipe connector, the combination of a connector head having an orificed face adapted to be presented to a companion connector head, said face being formed with a guideway lying approximately in the plane of said face; a gasket carrier confined in said guideway, capable 15 of withdrawal therefrom and formed with a flange-receiving recess serving to confine a gasket in sealing relation with said head around said orifice; and a flanged gasket mounted in said carrier and projecting 20 through the same with its flange confined in said recess.
10. In an automatic train pipe connector, the combination of a connector head having an orificed face adapted to be presented to a companion connector head; a gasket serving 25 to seal around said orifice; a gasket carrier serving to confine said gasket in place; and retaining means for said carrier serving to permit the withdrawal of said carrier across said face, whereby said carrier and gasket 30 may be withdrawn without interference by said companion connector head while the heads are in close proximity.
11. In an automatic train pipe connector, the combination of a connector head having an orificed face adapted to be presented to a companion connector head, said face being formed with a guideway lying approximately in the plane of said face; a gasket 35 carrier mounted in said guideway, capable of withdrawal therefrom and serving when in position to confine a gasket in sealing re-
- lation to said head around said orifice; and a gasket mounted in said carrier and capable of withdrawal therewith. 50
12. In an automatic train pipe connector for railway cars, the combination of a support carried by the car; a connector head movably mounted on said support and having an orificed face adapted to be presented to a companion connector head on an adjacent car; a spring urging said head in a direction to engage said companion head; abutments on said head and support offering engagement to force-applying means for 60 temporarily holding said connector head back in opposition to said spring; a gasket carrier slideable into position across the orificed face of said head and serving, when in position, to hold a gasket around said orifice; a gasket mounted in said carrier; and releasable retaining means for said carrier accessible in the coupled condition of said cars. 65
13. In an automatic train pipe connector for railway cars, the combination of a support carried by the car; a connector head movably mounted on said support and having an orificed face adapted to be presented to a companion connector head on an adjacent car; a spring urging said head in a direction to engage said companion head; abutments on said head and support offering engagement to force-applying means for 70 temporarily holding said connector head back in opposition to said spring; a gasket carrier slideable into position across the orificed face of said head and serving, when in position, to hold a gasket around said orifice; a gasket mounted in said carrier and 75 freely removable from the rear thereof when the carrier is withdrawn; and releasable retaining means for said carrier accessible in the coupled condition of said cars. 80
- In testimony whereof we have signed our 85 names to this specification.

BLYTHE J. MINNIER.
HENRY F. BICKEL.
